UNITED STATES PATENT OFFICE.

FRANK E. ORMSBY, OF CHICAGO, ILLINOIS, ASSIGNOR, BY MESNE ASSIGNMENTS, TO
H-B CORPORATION, OF OTTAWA, ILLINOIS, A CORPORATION OF ILLINOIS.

IRONING MACHINE.

Application filed August 27, 1920. Serial No. 406,362.

To all whom it may concern:

Be it known that I, FRANK E. ORMSBY, a citizen of the United States, residing at Chicago, in the county of Cook and State of Illinois, have invented certain new and useful Improvements in Ironing Machines, of which the following is a description.

My invention belongs to that general class of devices designed for smoothing or ironing fabrics or garments, sometimes generally termed "mangles," and has for its object the production of such a device, simple and effective in its operation. To this end it consists in the novel construction, arrangement and combination of parts herein shown and described, and more particularly pointed out in the claims.

In the drawings, wherein like reference characters indicate like or corresponding parts,

Figure 1 is a front view of my improved device;

Figure 2 is an end view of the same taken from the right;

Figure 3 is a transverse vertical section taken substantially on line 3-3 of Figure 1;

Figure 4 is a partial end view taken from the right illustrating a different position of the parts;

Figure 5 is a partial end sectional view substantially the same as Figure 3, showing the parts in a different position;

Figure 6 is a section taken substantially on line 6-6 of Figure 2; and

Figure 7 is a detail view.

In the drawings, 1 represents a suitable support which may be a table, or more conveniently a receptacle provided with doors 2-2 or equivalent construction as indicated in Figure 1. Upon the upper surface of the support or table is arranged my improved device, suitably supported by end pieces 3 and 4. Near one side or edge is provided a shoe 5 extending substantially the full length of the table, preferably pivotally supported on a pipe 6, which serves to conduct a heating medium to the shoe in the usual manner. This medium may be steam in large machines, or preferably in smaller machines it is suitably constructed to heat the shoe by a medium such as gas, electricity or gasoline.

A rotatable cylinder 7 which may be suitably padded is arranged substantially par-

allel to the shoe 5 and is mounted in such manner that the position of the cylinder in relation to the shoe may be controlled and regulated as desired. In the preferred form shown, the cylinder is mounted upon a suitable shaft 8 which has its ends positioned in slots 9 formed in the supports 3 and 4. Each end of the shaft is also mounted in a frame 10 and retained in relative position therein by springs 11 arranged to resiliently press the shaft in a direction toward the shoe. The frames 10 are mounted upon the supports 3 and 4 so as to be slidable relative thereto, and means are provided to force the frames toward the shoe as desired. The various elements are preferably duplicated at the ends with the exception of the driving means which need be provided at one end only.

In the preferred form shown, tilt levers 12-14 are pivotally supported on the supports 3 and 4 as at 13 having the end 14 bent upward and provided with ratchet teeth 15. A cooperating pawl 16 is pivotally supported on the support as at 17 so that as the part 14 is raised, the pawl will engage therewith and hold it in the elevated position. A link 18 is pivotally engaged with the part 12 and extended downward, and is attached to a treadle 19 which constitutes a lever pivoted between its ends, so that upon depressing the outer end of the lever 19, the link 18 will be lifted, elevating the part 14. A spring 20 connected to the part 12 and to some fixed part of the device as at 21, serves to automatically draw the lever 12-14 back to its normal position when the pawl 16 is released. Any preferred means may be employed to conveniently release the pawl. As shown, a board 22 extending parallel to and preferably about level with the top of the cylinder serves the double purpose of a support in passing and guiding the fabric upon the cylinder and as a releasing lever. As shown, the board may be pivotally supported to the frame as at 23 with a depending finger 24 extending beneath the free end of the pawl 16. A slight lift of the free edge of the board 22 will therefore disconnect the pawl from the ratchets 15, which will permit the lever 12-14 to fall to its normal position. The spring 25 or other preferred means may be employed to resiliently maintain the pawl in proper operative position. As an alter-

- native construction, which, however, may be used in connection with the construction just described, the pawl may be provided with an extending arm 26 which may be operated 5 from the outside of the device and serve to release the pawl without disturbing the table 22. Also as an alternative construction, which, may, however, be used in connection with the treadle lever 19, a hand lever 27, 10 conveniently arranged, may be pivotally connected as at 28, engaging the link 18 at 29. The operation of this lever will likewise serve to elevate the tilt lever 12-14 as described. 15 The frames 10 at their outer or free ends operatively engage or contact with the lever 12-14, so that as the latter is lifted in the manner described, the shaft 8 will be forced forward in the slots 9, carrying the 20 cylinder 7 into proximity to or contact with the curved face of the shoe 5. This contact is resiliently maintained by means of the springs 11. Upon the outer end of the shaft 8, preferably exterior to the support 3, is 25 rigidly mounted a cog or gear wheel 30, clearly shown in Figures 2 and 4. Normally, that is, when the lever 12-14 is at the downward limit of its movement, the cog wheel 30 is disengaged, but as it is 30 forced forward with the shaft in the manner described, it automatically engages with a cooperating gear wheel 31 which may be driven in any preferred manner. As shown, the gear wheel 31 is connected to and forms 35 a part of a gear wheel 32 meshing with the worm gear 33 driven by a motor 34.
- While this is a very convenient means of driving the same, any other preferred means may be employed for that purpose. 40 As thus described, it will be apparent that, upon elevating the tilt-lever 12-14, the cylinder 7 will be caused to approach the shoe, and the gear wheel 30 to engage the cooperating gear wheel 31 and be driven thereby. 45 The cylinder is resiliently forced against the shoe which is heated as stated, and the fabric supported upon the shelf 22 and extended to the cylinder between the latter, and the shoe will be resiliently forced 50 against the smooth surface of the latter as the cylinder rotates. The pressure may be regulated as desired by the foot lever 19. The cylinder may be instantly released by disconnecting the pawl from the ratchet 55 teeth 15 of the lever 14 in either of the ways described.
- In some cases it may be desired to control the operation of the device by the foot lever 19 or hand lever 27 without the use 60 of the pawl 16. To provide for this, I have arranged a latch 35 (Figures 3 and 5) provided with a hooked end 36 which may be pressed downward to engage the end of the pawl 16 and hold the same out of operation. 65 The pawl may be released by depressing the

free end of the latch, as clearly shown. When the pawl is thus held out of operation, the cylinder is held in position to smooth or iron the goods by means of the foot or hand lever alone. If the former is used, it will leave both hands free to manipulate the goods, and the most delicate manipulation is thus made possible. Upon releasing the cylinder and its gear wheel 30, the cylinder is easily rotated in the reverse direction for the removal of the goods. The usual ball bearing or other anti-friction devices may be employed throughout with good effect.

In some instances it may be desired to move the shoe 5 back from its normal position. Inasmuch as it is pivotally supported upon the pipe 6, this may be readily accomplished as shown in dotted lines in Figure 3, handles 37 upon the face of the shoe 85 or equivalent means being provided for convenience.

A simple latch or connecting member of any desired construction may be employed to hold the shoe in relative position for operation. The simple means shown, more clearly illustrated in Figure 7, consists of a thumb screw 38 passing through the end supports and with its end engaging an aperture in the end of the shoe 5. Retracting 95 the screw will release the shoe and permit it to be moved backward as indicated.

The tilt lever 12-14 is preferably duplicated at each end to secure reliable operation, and the various levers and parts described preferably extend across the full length of the face of the machine for convenience in operating, so that at whatever point the operator may employ these devices, the operation will be effected at each 100 end of the cylinder as described.

Having thus described my invention, it is obvious that various immaterial modifications may be made in the same without departing from the spirit of my invention; 110 hence I do not wish to be understood as limiting myself to the exact form, construction, arrangement and combination of parts herein shown and described, or uses mentioned.

What I claim as new and desire to secure 115 by Letters Patent is:

1. In a device of the kind described, a polishing shoe pivotally supported to be brought into relative operative position or to be swung backward therefrom into inoperative position, and means for heating the shoe, in combination with a rotatable shaft arranged parallel to the working face of the shoe with its ends extended and positioned in guide-ways, a cooperating cylinder 120 mounted upon the shaft, tilting levers for each end of the shaft, resilient means arranged between the tilting levers and the ends of the shaft, means for operating the tilting levers to move the shaft laterally to 125 130

- bring the cylinder into resilient operative relation with the shoe, and automatically operable means for detachably latching the tilting levers in such position.
- 5 2. In a device of the kind described, a pivotally mounted polishing shoe, and means for heating the same, in combination with a rotatable shaft arranged parallel to the working face of the shoe with its ends 10 extended and positioned in guide-ways, a cooperating cylinder mounted upon the shaft, a tilting lever for each end of the shaft, resilient means arranged between the tilting levers and the ends of the shaft, a 15 foot lever arranged to operate the tilting levers to bring the cylinder into resilient operation with the shoe, and means for temporarily automatically locking the tilting levers in such position and independent of 20 said foot lever for manually releasing the same at will.
3. In a device of the kind described and in combination, a polishing shoe pivotally supported to be rocked forward and maintained in relative operative position or to be swung backward from such position, means for heating the shoe, a rotatable shaft arranged parallel to the working face of the shoe with its ends extended and positioned 25 30 in guide-ways, a cooperating cylinder mounted upon the shaft, a tilting lever for each end of the shaft, a box for each end of the shaft provided with a slot therein in which the end of the shaft is located, resilient means positioned in the box between the shaft and the end of the box, the extended end of the box being secured to the tilting levers, a foot lever arranged to operate the tilting levers, and latching means 35 40 for automatically maintaining the tilting levers in their advanced or operative posi-
- tion, and independent of said foot lever releasing the same therefrom at will.
4. In a device of the kind described, a rotatable shaft with its ends positioned in 45 guide-ways, and with a cylinder mounted thereon, a tilting lever for each end of the shaft provided with resilient means between the lever and the shaft, said levers provided with ratchet teeth upon the free 50 end, in combination with a cooperating pawl arranged to engage the ratchet teeth as the tilting lever is moved in one direction, and means for temporarily locking the pawl in inoperative position. 55
5. In a device of the kind described, a rotatable shaft having its ends positioned in guide-ways and having a cylinder mounted thereon, block members mounted upon the free ends of the shaft provided with a 60 slot, resilient members arranged in the slot and adapted to hold the shaft at the extreme end of the block, a tilting lever for each end of the shaft, having its free end bent at an angle and provided with ratchet 65 teeth, the free end of the block and the tilting lever being operatively engaged, in combination with a cooperating pawl for the ratchet face of the tilting lever, a pivoted table provided with a finger extended and 70 adapted to disengage the pawl as the table is lifted, and a locking member adapted to temporarily lock the pawl out of engagement. 75

In testimony whereof, I have hereunto signed my name in the presence of two subscribing witnesses.

FRANK E. ORMSBY.
